UNITED STATES PATENT OFFICE.

WILLARD M. MATTHEWS, OF NEW BEDFORD, MASSACHUSETTS.

DIRECTION-INDICATOR.

1,295,783.

Specification of Letters Patent. Patented Feb. 25, 1919.

Application filed October 2, 1915. Serial No. 53,816.

To all whom it may concern:

Be it known that I, WILLARD M. MATTHEWS, a citizen of the United States, residing at New Bedford, in the county of 5 Bristol and State of Massachusetts, have invented certain new and useful Improvements in Direction-Indicators; and I do hereby declare the following to be a full, clear, and exact description of the invention, 10 such as will enable others skilled in the art to which it appertains to make and use the same.

This invention relates to new and useful improvements in direction indicators, and 15 the principal object of the device is to provide a means for efficiently indicating to pedestrians and vehicles the direction in which the vehicle on which the device is used, will travel.

20 Another object of the invention is to provide a simple and efficient means operable from the seat of the driver of the vehicle to indicate at both ends of the vehicle the direction to be taken.

25 A further object of the invention is to provide an electrically operated means which is particularly simple in construction and cheap to manufacture, thus placing the device within reach of all persons to whom 30 such a device would be useful.

Still another object of the invention is to provide a device wherein the signals are independently operable, thereby enabling the driver to selectively indicate at both ends 35 of the vehicle the direction to be taken.

A further and equally important object of the invention is to provide a device which will serve to save life and property from damage through misunderstanding of signals. 40

With these and other objects in view, the invention consists in the novel combination and arrangement of parts which will be fully set forth in the following specification 45 and accompanying drawings, in which:

Figure 1 is a face view in elevation of one of the signal boxes, illustrating the stop signal being given,

Fig. 2 is a transverse sectional view on 50 line 2-2 of Fig. 1,

Fig. 3 is a horizontal sectional view on line 3-3 of Fig. 2,

Fig. 4 is a detail view of one of the indicating arrows,

55 Fig. 5 is a detail view of the opposite indicating arrow,

Fig. 6 is a view of still another of the signal plates, and

Fig. 7 is a view illustrating the wiring diagram of the device. 60

Referring to the drawings the numeral 1 designates as an entirety the casing of the device comprising a bottom 2 formed with the front wall 3 and the end walls 4. The rear wall designated 5 may be hinged or 65 rigidly secured to the device in any suitable manner, and the front wall 3 is formed with the sight opening 6, in which a suitable glass panel may be secured if desired. It is to be understood that the glass panel above referred to, need not necessarily be of glass, but may be formed of any other suitable transparent material, through which the signals may be readily seen. Secured to the wall 3 at a point directly above the opening 6 is the support arm or flange 7, the rear end of which has secured or formed integral therewith the back panel 8, forming the rear of the sight chamber, indicated by the numeral 9. A suitable stop 10 is secured to the inner face of the rear of the bottom 2 and forms a rest against which the signaling plates bear when in their inoperative position. 70

Secured within the casing or housing 1 in 85 the rear of the plates or back 8 and at spaced intervals within said housing are the electromagnets 11 provided with the usual magnetic cores which are adapted to attract the armatures of the various signals as will be 90 more fully hereinafter described.

Mounted between the end walls 4 at a point slightly above and forward of the magnets 11 is a rod 12 on which the frames carrying the indicating plates are pivoted. 95 These frames comprise the U-shaped members 13, the ends of the arms of which are formed with suitable loops or bearings 14, which are pivotally mounted on the rod 12 and one of said arms extended, as at 15, 100 and carries a soft iron armature 16, which is adapted to be attracted by the core of the magnets 11 when any one of said magnets is energized. It is to be understood that there is provided a frame 13 and an armature 16 for each signal plate and the signal plates designated by the character 17 are secured to the bight portions of the U-shaped frames in such a way as to be held directly in line with the sight opening when 110 the frame is in its raised position.

The indicating plate, designated by the

character A, is formed with a black outer surface and is provided with a cut-out portion 18, behind which is supported a suitable panel 19 of white translucent material. 5 The cut-out portion 18 may be in the shape of a hand, arrow or any other suitable direction indicating means, which points in one direction, so as to indicate that the vehicle will take the direction in which the hand points upon the energization of the magnets for actuating the plate A. The plate designated by the character B, like the plate A, is provided with an opening 20 behind which a suitable glass panel 21 is secured, and this opening 20 is arranged so that it points in a direction opposite to the direction of the opening 18. The plate, designated by the character C, is provided with a plurality of perforations or cut-out portions 22 behind which suitable glass panels of translucent white glass 23 are secured, and these perforations are preferably in the form of letters to indicate the word "Back", thereby indicating when in its operative position that the vehicle will travel in a reverse direction. Like the panel C, the panel D is provided with the perforations or cut-out portions 24 provided with the translucent glass panels 25 at their rear sides, which cut-out portions or perforations are in the form of letters forming the word "Stop", thereby indicating the intention of the driver to bring the vehicle to a standstill. From the foregoing it will be seen that upon moving any one of the indicating panels A, B, C or D, into alinement with the sight opening, the various indications or signals, as to the intention of the driver, may be given, thus warning persons approaching the vehicle from the front or rear, and avoiding many accidents.

Referring to the wiring diagram illustrated in Fig. 7, the character 26 designates the power source from which leads the wire 45 27, and leading from the opposite terminals of the power source is the wire 28. This wire 27 leads to one terminal of the magnet 11 in one of the housings or casings 1, and thus acts as a feeder for said magnets, while 50 the wire 28 leads to one terminal of the magnet 11 in the housing 1 at the opposite end of the vehicle. The magnet for operating the signal plate, designated by the character A, is designated by the character 55 a, and leading therefrom is the wire 29, one terminal of which is connected to one pole of the switch a'. The opposite terminal of this switch is connected by means of the

wire 30 to the terminal of the magnet A at the opposite end of the vehicle opposite the 60 terminal which is connected to the wire 28. It will thus be seen that as the switch A' is thrown to close a circuit through the magnet, the various magnets at the forward and rear end of the vehicle, will be energized, 65 thereby moving the indicating plate A into indicating position. It will likewise be noted that the current flowing from the battery upon the closing of the switch B', will pass through the wire 27 into the magnet b 70 and then through the wire 31 to one of the poles of the switch B' and thence from the opposite pole through the wire 32 into the magnet c at the opposite end of the vehicle, and thence back through the wire 28 to the 75 battery. The closing of the remaining switches C and D selectively will respectively energize their magnets c and d, so as to operate the signals and indicate to the person approaching the vehicle from either 80 direction the intention of the driver.

While in the foregoing there has been shown and described the preferred embodiment of this invention, it is to be understood that such changes may be made in the 85 combination and arrangement of parts as will fall within the spirit and scope of the appended claim:

What is claimed is:—

A direction indicator comprising a housing having a sight opening, a pivot bar located within the housing, a plurality of U-shaped frames, certain of said frames having a relatively short arm and a relatively long straight arm, and the other of said 95 frames having each a relatively short arm and a relatively long angular arm, said short arms having bar receiving bearings at their free ends and the relatively straight long arms having bar receiving bearings spaced 100 from their rear ends in alinement with the first bearings and the relatively long angular arms each having a pair of bar receiving bearings alining with said other bearings, an armature carried by each long arm, electro-magnets carried by the casing, a source of power for the electro-magnets, a switch mechanism, and a direction indicating plate carried by the bight portion of each frame.

In testimony whereof I affix my signature 110 in presence of two witnesses.

WILLARD M. MATTHEWS.
